UTENSIL SUPPORTING RACK

Kenneth S. Jenson, Wisconsin Rapids, Wis., assignor to Prentiss Wabers Products Company, Wisconsin Rapids, Wis., a corporation of Wisconsin

Application April 11, 1950, Serial No. 9,121

Term of patent 3½ years

(Cl. D44—29)

To all whom it may concern:

Be it known that I, Kenneth S. Jenson, a citizen of the United States, residing at Wisconsin Rapids, in the county of Wood and State of Wisconsin, have invented a new, original, and ornamental Design for a Utensil Supporting Rack, of which the following is a specification, reference being had to the accompanying drawing, forming part thereof wherein—

Figure 1 is a perspective view of a utensil supporting rack showing my new design;

Fig. 2 is an enlarged side elevational view of the rack with a portion broken away for convenience of illustration; and

Fig. 3 is an enlarged front elevational view thereof.

I claim:

The ornamental design for a utensil supporting rack, as shown.

KENNETH S. JENSON.
